CLAIM

The ornamental design for a structure for casting manufacturing, as shown and described.

DESCRIPTION

The patent or application file contains at least one drawing executed in color. Copies of this patent with color drawing(s) will be provided by the Office upon request and payment of the necessary fee.

FIG. 1 is a perspective view of a structure for casting manufacturing according to our new design;

FIG. 2 is a front elevational view thereof;

FIG. 3 is a left side elevational view thereof;

FIG. 4 is rear elevational view thereof;

FIG. 5 is right side elevational view thereof;

FIG. 6 is a bottom plan view thereof;

FIG. 7 is a top plan view thereof;

FIG. 8 is a cross-sectional view thereof across line 8-8 of FIG. 7;

FIG. 9 is a perspective view of FIG. 8;

FIG. 10 is an enlarged view thereof corresponding to section lines 10-10 of FIG. 8; and,

FIG. 11 is an enlarged view thereof corresponding to section lines 11-11 of FIG. 9.
